LAMP FOR COLORED LIGHT TREATMENT

Gertrude E. Kothe, New York, N. Y.

Application September 3, 1932, Serial No. 631,676

1 Claim. (Cl. 128—396)

This invention relates to lamps for colored light treatment, to be employed in beauty, therapeutic and other similar treatments. Treatment by colored light has been practiced for a long time but the lamps used have been unsatisfactory for various reasons. One of the chief defects of such lamps was that they were constructed so that only a small part of the body could be treated at one time. Another defect was that the radiation given off by such lamps was concentrated to such an extent that great care was necessary to avoid burning or otherwise injuring the skin of the person treated.

The present invention aims to provide an improved lamp which will deliver well distributed light of the desired color over the entire upper part of the head, and which is convenient to use and efficient in operation, and has other advantages which will appear from the following description.

To these ends the invention consists in the features of construction, arrangement and combination of parts hereinafter described and illustrated in the drawing and specifically pointed out in the claim.

One approved embodiment of the invention is illustrated, by way of example, in the accompanying drawing, wherein—

Fig. 1 is a vertical, central section through a lamp designed to treat the upper part of the head;

Fig. 2 is a side elevation of the lower part of the lamp with the light screen partially separated from the lamp housing;

Fig. 3 is a bottom plan view of the lamp; and

Fig. 4 is a detail section on the line 4—4 of Fig. 3.

The lamp shown comprises three main parts, a housing 10, a reflector 11 which carries the electric light bulbs 12, and a color screen generally designated as 13. The housing and the reflector have substantially hemispherical top portions, and the top of the housing is spaced away from the top of the reflector. The housing serves a double function. In the first place, by being spaced apart from the reflector, except around the lower part thereof, it provides a heat-insulating air space around the hot upper part of the reflector. Air-holes 14 are provided in the top of the housing to permit the escape of heated air. In the second place, it serves to conceal the lamp supports 15 on the top of the reflector. A handle 16 is attached to the housing to enable the lamp to be readily moved or, if desired, suspended from any convenient support.

A cable 17 passing through an aperture in the housing supplies current to the lamps.

The color screen 13 is substantially hemispherical in form, its radius being somewhat greater than that of the average head, so that the lamp may be placed over the patient's head, as shown, with the screen spaced away from the head more or less uniformly at all parts. This construction permits circulation of air for the purpose of carrying off a part of the heat generated by the lamp. The reflector is considerably longer than the usual parabolic reflector and the lower portion is cylindrical, or nearly so, for the purpose of directing the reflected light inwardly onto the sides of the light screen, as indicated by the arrowed lines 20 and 21, instead of directing it downward in parallel rays. The distance between the top of the screen and the top of the reflector is usually about half the width of the reflector at its widest part, and should, except in exceptional cases, be in excess of one-third of such width. The reason for this construction is that the top of the screen receives a greater proportion of light per unit area direct from the lamps than do the sides. Not only are the sides of the screen further from the lamps than the top, but also the direct rays from the lamps strike the sides at an increasingly oblique angle and do not even strike the lowermost part of the screen at all. Both of these factors reduce the light per unit area received direct from the lamps by the sides of the screen. To compensate, in part at least, for these differences in the amount of direct light, the reflector is designed, as above described, so as to direct a large proportion of the reflected light on the sides of the screen. The inner surface of the reflector is desirably slightly corrugated, as shown, to increase the dispersion of the light from the lamps.

If a single source of light were used, the light rays would, even with the construction above described, tend to be concentrated more than is desirable in a certain zone or zones. Therefore, to obtain better and more uniform distribution of the light, a plurality of spaced sources of light, such as the three lamps 12, are used. The location of the lamps, or at least some of the lamps, off center with respect to the reflector also aids in throwing a larger proportion of light on the sides of the screen than would otherwise be the case.

The color screen as shown comprises two annular frames 25 and 26, hingedly connected at 27, and two hemispheres 28 and 29 of wire mesh, one carried by each of the frames 25 and 26, between

- which a sheet 32 of colored gelatin, Cellophane or the like is held. The sheet 32 is positioned by swinging the frames away from each other and placing the sheet over the wire-mesh hemisphere 29, and then swinging the frames with their wire-mesh hemispheres together into the position shown in Fig. 1. The colored sheet 32 is thereby deformed into hemispherical shape and held in such shape by the wire mesh hemispheres. If at any time a different colored screen is required, the frames are separated and the sheet therebetween replaced by a sheet of the desired color. The frames are releasably held together by spring clips 33 as shown in Fig. 4.
- 15 The screen as a whole is releasably attached to the bottom of the housing by a pair of upstanding slotted spring clips 35 mounted on the frame 25 adapted to engage wedge-shaped projections 37 on the lower part of the housing.
- 20 In the use of the invention, the lamp is placed over the head of the person to be treated, as shown by Fig. 1, the lamp being held so that the color screen 13 is spaced away from the head so that because of the size of the screen recess air may circulate and carry off some of the heat from the lamp. The light from the light bulbs 12 is directed by the reflector 11 against the color screen

so that the desired rays of colored light from the screen will be projected directly against all parts of the person's head within the screen.

What is claimed is:

A lamp for colored light treatment, comprising 5 a curved top reflector having a substantially hemispherical top portion and a lower substantially cylindrical portion, a source of light in the upper part of the reflector, a color screen for receiving and transmitting light from the reflector comprising 10 two wire-mesh members of similarly upwardly curved cross-section separably connected together and a sheet of colored translucent material between said wire-mesh members and deformed by the latter into correspondingly curved 15 form, and means for detachably securing the color screen in position, said wire mesh members and curved translucent material being located within the lower cylindrical portion of the reflector and being of sufficient size to receive completely 20 the upper part of the head of a person so that rays of colored light will be directed downwardly upon the head by the top portion of the reflector and inwardly entirely around the head by the lower portion of the reflector. 25
